UNITED STATES PATENT OFFICE

2,484,363

PENCIL HOLDER FOR TELEPHONES

Merle J. West, Los Angeles, Calif., assignor of one-half to F. B. Page and one-half to J. A. Sparkman, Huntington Park, Calif.

Application December 12, 1947, Serial No. 791,331

6 Claims. (Cl. 24—10)

1

My invention relates to pencil holders which are arranged for attachment to a dial telephone, and included in the objects of my invention are:

First, to provide a pencil holder which is arranged for attachment to the finger stop of a dial telephone but which does not in any manner damage the telephone or interfere with its use.

Second, to provide a pencil holder of this type which may be readily and quickly fastened in place or removed without the use of tools but which remains secure against accidental dislodgment.

Third, to provide a pencil holder which incorporates novel clamping means for effecting a yieldable but firm grip on the finger stop of a telephone.

Fourth, to provide a pencil holder which presents a readable, visible area suitable for an advertising message.

With the above and other objects in view as may appear hereinafter, reference is directed to the accompanying drawings, in which:

Figure 1 is a perspective view of my pencil holder.

Figure 2 is a top or plan view thereof indicating by broken lines the relative position of the finger stop and dial of a telephone.

Figure 3 is a side elevational view thereof as viewed from the plane 3—3 of Figure 2.

Figure 4 is a sectional view thereof taken through 4—4 of Figure 2.

Figure 5 is a fragmentary sectional view through 5—5 of Figure 2 showing particularly the clamp jaws and their relationship to the finger stop of a telephone.

Figure 6 is a fragmentary sectional view in the same plane as Figure 4 showing a modified form of journal for the clamp lever.

Figure 7 is a similar sectional view showing another modified form of journal for the clamp lever.

My pencil holder includes a base plate which is semicircular in form. One edge is straight and is provided with a strip 2 which is folded under the plate and connected thereto by a web 3. The web 3 does not extend the length of the strip 2 but terminates to form a slot 4 between the strip 2 and the base plate 1.

The strip 2 is provided at its free extremity with a notch 5 disposed in an acute angular relation to the longitudinal axis of the strip. The base plate is provided with a notch 6 located vertically above the notch 5. The two notches form spaced fixed jaws of a clamp.

Pivotedly mounted between the strip 2 and the

2

base plate 1 by means of a journal pin 7 is a lever 8. One end of the lever 8 protrudes through the slot 4 and is provided with a notch 9 disposed in an acute angular relation with the longitudinal axis of the lever to form the movable jaw of a clamp. The notches 5 and 6 are so related to the notch 9 that they fit over and grip opposite edges of the upright portion A of a telephone finger stop B.

The lever 8 includes an arm 10 extending under the base plate 1 and terminating in a depending portion 11. A spring 12 is connected to the depending portion 11 and to the strip 2 at its extremity remote from the notch 5. The spring 12 is relatively stiff, and the length of the arm 10 is substantially greater than the portion of the lever having the movable jaw or notch 9 so that the jaws grip the finger stop tightly.

The base plate 1 preferably extends laterally from the finger stop in a plane more or less parallel with the dial of the telephone. The surface of the base plate 1 is preferably flat and is adapted to receive a correspondingly shaped advertising card 13 which may be secured thereto by tongues 14 struck from the surface of the plate.

A pencil mounting tongue 15 extends downwardly and outwardly from the curved margin of the base plate 1. The tongue 15 is provided with a hole 16 adapted to receive a pencil or other writing implement.

In the construction as shown in Figures 2 and 4 a journal pin 7 is provided which protrudes through the base plate 1. It is not necessary that the journal for the lever 8 extend through the base plate. First, the strip 2 may be provided with an upwardly directed extrusion 17, as shown in Figure 6, over which the lever 8 is fitted before the strip 2 is folded to its final position. Alternatively, a journal 18 may be formed by a staking operation, as shown in Figure 7.

Having fully described my invention, it is to be understood that I do not wish to be limited to the details herein set forth, but my invention is of the full scope of the appended claims.

I claim:

1. A pencil holder adapted for attachment to the finger stop of a dial telephone, involving: a plate having a folded and slotted margin; a dual fixed jaw formed in said slotted margin and arranged to fit an edge of a telephone finger stop; a lever pivotally connected to said plate and having a jaw portion extending through said slotted margin and arranged to engage the edge of said

telephone finger stop opposite from the edge engaged by said fixed jaw; yieldable means urging said jaws in gripping relation; and means for supporting a pencil relative to said plate.

2. An attachment for the finger stop of a dial telephone, involving: a plate having a folded and slotted margin; a dual fixed jaw formed in said slotted margin and arranged to fit an edge of a telephone finger stop; a lever pivotally connected to said plate and having a jaw portion extending through said slotted margin and arranged to engage the edge of said telephone finger stop opposite from the edge engaged by said fixed jaw; and yieldable means urging said jaws into gripping relation.

3. An attachment for the finger stop of a dial telephone, involving: a plate; a fixed jaw located at an edge of said plate; a lever pivotally connected to said plate and having a movable jaw coacting with said fixed jaw to grip opposite edges of the finger stop of a dial telephone; and yieldable means between said lever and plate to cause said jaws to grip said finger stop.

4. A pencil holder adapted for attachment to the finger stop of a dial telephone, involving: a plate; a fixed jaw located at an edge of said plate; a lever pivotally connected to said plate and having a movable jaw coacting with said fixed jaw to grip opposite edges of the finger stop of a dial telephone; yieldable means between said lever and plate to cause said jaws to grip said finger stop; and an extension directed outwardly and downwardly from said plate and perforated to receive a writing implement.

5. An attachment for the finger stop of a dial telephone, involving: a plate including a marginal strip folded under said plate and spaced therefrom; a lever member pivotally mounted

between said plate and marginal strip and protruding therefrom; the edges of said strip and plate and the protruding extremity of said lever shaped to form confronting jaw elements adapted to engage and grip opposite sides of the finger stop of a dial telephone to support said plate in a laterally extended position relative to said finger stop; and yieldable means urging said jaws into their gripping relation.

10 6. A pencil holder adapted for attachment to the finger stop of a dial telephone, involving: a plate including a marginal strip folded under said plate and spaced therefrom; a lever member pivotally mounted between said plate and marginal strip and protruding therefrom; the edges of said strip and plate and the protruding extremity of said lever shaped to form confronting jaw elements adapted to engage and grip opposite sides of the finger stop of a dial telephone to support said plate in a laterally extended position relative to said finger stop; yieldable means urging said jaws into their gripping relation; and an extension directed outwardly and downwardly from said plate and perforated to receive a writing implement.
